Germany

Application May 25, 1932, Serial No. 613,393
In Germany June 18, 1931

6 Claims. (Cl. 179—18)

The invention relates to a circuit arrangement for automatic telephone systems having a plurality of exchanges in which connections of various traffic directions may be set up over the same 5 group of junction lines.

In known arrangements of this type the incoming end of the junction line is generally connected to a switching device of such a construction that, on the seizure of the line, it is connected to a 10 switch or the like which connects said line to the line group terminating in the contact row over which the junction line is seized at its outgoing end. This switching device is influenced by varying potentials being applied to the outgoing end 15 of the line and accordingly connects the line to the appropriate line group.

This type of arrangements, however, are impaired by the defect that only a limited number of line groups can be selected at the incoming end 20 of the junction line due to the fact that only a limited number of potential combinations is possible.

The present invention eliminates this defect by 25 making it possible to select any number of line groups. This is accomplished by associating the connecting devices at the outgoing end of the junction line with switching means which function when definite traffic directions are selected and transmit over the junction line a frequency 30 or a combination of frequencies corresponding to the required direction which causes a switch at the incoming end of the line to be set accordingly.

An embodiment of the invention is shown in the drawing. An arrangement is illustrated by 35 which connections from a sub-exchange provided with the group selector GW1, the secondary lineswitch MW and the repeater Ue2 may be set up over the junction line VL to a main exchange in which the group selector GW2 (in the form of a 40 one-directional switch having a plurality of contact groups) is arranged, as well as connections within the sub-exchange completed over the group selector GW1 and the repeater Ue1. The switch wiper sa1, during the setting operation on 45 the part of the group selector GW1, is raised, together with the other wipers of the switch, to contact segments, of which those brushed by the wiper during the setting of connections to the main exchange are connected to alternating current 50 sources of supply from which emanate the various frequencies f1, f1+f2, f1+f2+f3.

In principle the arrangement operates as follows:

If a connection is to be set up from the sub-ex- 55 change to the main exchange, the secondary line-

switch MW is set to the repeater Ue2 when the group selector GW1 is seized. According to the level to which said group selector GW1 has been raised after its setting a definite frequency f1 or combination of frequencies f1+f2 or f1+f2+f3 is 60 transmitted over the junction line determined by the frequency in the group of junction lines corresponding to the contact groups I, II or III brushed by the switch wiper sa2.

The device operates in detail as follows: Relays 65 A and C1 are energized and actuate their respective contacts when, for the purpose of completing a connection to the main exchange, the preceding connecting device seizes the group selector GW1 in known manner. The closing of contact 8c1 causes the rotary magnet DS of the secondary lineswitch MW to be intermittently energized and deenergized over earth, interrupter RU1, contacts 8c1, 11q, 12o, rotary magnet DS, battery, earth with the result that it continues to 70 advance the secondary lineswitch until it has encountered an idle succeeding repeater Ue2. Relay Q is then energized over earth, contacts 10c1, 13o, relay Q contact 14r, wiper 3 of the secondary lineswitch, c-lead, contacts 15f, 16h1, resistance, bat- 75 ttery, earth. Relay Q opens its contacts 11q and thereby cuts off the circuit for the rotary magnet DS, thus causing the secondary lineswitch to be brought to rest. It also closes its contacts 28q and 39q. 80

When the group selector GW1 now receives the impulses transmitted by the subscriber, relay A accordingly is intermittently energized and de-energized. Contact 1a is re-closed on the first deenergization on the part of relay A and this 90 causes relays V and E1 to be energized over earth, contact 7c1, relay V, contact 1a, relay E1, battery, earth. Relay E1 closes its contact 17e1 with the result that, simultaneously with the release of relay A which caused contact 3a to be closed, the following circuit for the vertical magnet H of the switch is completed: earth, contacts 71p, 3a, 17e1, 20w, magnet H, battery, earth. The vertical magnet is then actuated in accordance with the number of impulses received and raises the wipers a, b, c and sa1 accordingly, at the same time closing the off-normal contact 19k on the first vertical step. At the end of the impulse series the switch wiper sa1, according to the number of impulses transmitted, is set to a contact segment to which the frequencies f1, f1+f2, f1+f2+f3 are applied. 100 The c-wiper of the group selector at this moment is set in front of the first contact of the level wherein the contacts are inter-connected according to the drawing. If the rotary magnet D1 is 105

If the rotary magnet D1 is 110

re-energized over earth, interrupter RU1, contacts 21p1, 18v, 19k, magnet D1, battery, earth after the release of relay V and consequently the c-wiper is actuated, relays P1 and R are energized over earth, contact 22e1, relay P1, c-wiper, relay R, battery, earth when said c-wiper is set to the first of the interconnected contacts. Relay R then throws over its contacts 27r and 14r into positions 37r and 38r. The closing of contact 38r causes relay F to be energized over earth, contacts 10c1, 13o, relay Q, contacts 38r, 39q, wiper 4, d-lead, relay F, battery, earth. Relay F throws over contact 29f into position 40f and thereby prepares the circuit for relay J1 for the transmission of the succeeding impulse series. Moreover, relay F closes contact 72f which connects up relay G thus causing relay H1 also to be re-energized over contact 73g.

The energization of relay R may now be retarded in such a manner that the contacts of the row to which the relay is connected are only interconnected from their second or one of the succeeding contacts. The circuit which extends over contact 27r then remains for a corresponding period with the result that the duration of the impulse transmitted over the junction line VL can be determined in this manner as indicated below.

A circuit over the current source of supply f_1 , switch wiper sa_1 , contacts 26v, 5a, 27r, 28q, switch wiper 1, a-lead, contacts 29f, 30j1, 32f, b-lead, switch wiper 2, contact 33r, earth, remains in operation until relay R has been energized due to the fact that the switch wiper sa_1 at the end of the impulse series is set to, for example, the segment which is connected to the alternating current source of supply having the frequency f_1 . Consequently an impulse of the frequency f_1 is transmitted to the group selector GW2 over the line VL. This impulse influences relay J2 which closes its contact 41/2 and consequently connects up relay S over its winding I. Relay S, when energized, closes its contact 42s with the result that it is maintained energized and also causes relay C2 to be energized in the following circuit: earth, contact 43p2, winding I of relay C2, contact 42s, winding II of relay S, battery, earth. Relay C2 closes contact 46c2, thus causing the rotary magnet of the switch GW2 to be intermittently energized in the following circuit: earth, interrupter RU2, contacts 47p2, 46c2, magnet D2, battery, earth and consequently to advance its switch wipers until they find an idle outgoing line. Due to the contacts 44c2 and 48s also having been closed on the energization of relays C2 and S, the group selector GW2 hunts for an idle junction line in group I by the switch wiper sa_2 being caused to brush this contact group in the following circuit: earth, contacts 44c2, 48s, 49t, 50u, wiper sa_2 , relay P2, c-wiper of the group selector GW2, outgoing c-lead. As soon as such a line is found relay P2 is energized and opens contact 47p2, thus cutting off the circuit for the magnet D2 with the result that the group selector is brought to rest. Relay P2, in addition, closes its contact 51p2 and thereby guards the group selector in known manner against further seizures, finally switching it through to the succeeding connecting device by means of contacts 52p2 and 53p2. Relay P2 also closes contact 54p2 with the result that the succeeding impulse series, received by relay J2 and transmitted to relay J1 by the intermittent closing of contact 4a and from this relay further extended over the junction line VL by the actuation of contacts 68j1 and 69j1, may

be transmitted over the outgoing a-lead to the succeeding connecting devices over contacts 70j2, 54p2, and 53p2.

If, on the other hand, the group selector GW1 has been raised to another level for the setting up of another connection from the sub-exchange to the main exchange, the switch wiper sa_1 at the end of the impulse series transmitted to the switch is set, for example, to the segment to which the frequencies f_1+f_2 are connected. If the group selector has been set to the repeater Ue2, a further impulse now indicating the frequencies f_1 and f_2 is transmitted over the junction line VL in the manner indicated above. Relays J2 and X in the group selector GW2 are energized by this impulse. Relay J2 again connects up relay S and this relay in turn relay C2 with the result that the circuit for the magnet D2 is closed over contact 46c2 and the switch starts to operate. Due to the fact that contact 56x is now closed by the energization of relay X, relay T also is energized over: earth, contact 48p2, winding I of relay C2, contact 56x, relay T, battery, earth. Relay T remains energized over its contact 57t and, in addition, throws over its contact 49t into position 58t. The switch wiper sa_2 , therefore, advances in the contact group denoted by II and hunts in this group for the outgoing c-lead of an idle junction line over: earth, contacts 44c2, 48s, 58t, 59u, switch wiper sa_2 , relay P2. Due to contact 64c2 also being opened on the energization of relay C2, relay E2 was energized over: earth, contact 45c2, winding II of relay C2, relay E2, battery, earth. Relay E2 disposes its contact 55e2 in position 71e2 and thereby disconnects relays X and Y from the a-lead. At the same time it switches through the a-lead.

In a manner similar to that described above, for example, for the setting up of a connection to the main exchange corresponding to a third traffic direction, alternating current impulses of the frequency $f_1+f_2+f_3$ are transmitted over the junction line VL and influence relays J2, X and Y so that in turn relays S, C2, T and U are energized and the group selector hunts in the line group denoted by III.

At the end of the conversation the switch preceding the group selector GW1 cuts off the c-lead in known manner, thus causing relay C1 to release. Relay E1 consequently releases due to the opening of contact 7c1 and opens its contact 22e1. This causes relays P1 and R to relapse. Contact 37r, therefore, is, restored to position 27r and contact 38r to position 14r. Due to the throwing over of the latter contact the circuit for relay F is cut off and contact 74f is closed. There is now a circuit for relay J1 over: earth, contacts 75h1, 74f, winding II of relay J1, battery, earth until relay G has been released due to the opening of contact 72f and, subsequently, relay H1 due to the opening of contact 73g, whereupon the circuit for relay J1 is cut off at contact 75h1. Relay J1, therefore, closes its contacts 68j1 and 69j1 during a period corresponding to the total release periods of the three relays G, H1, and J1 of a longer alternating current impulse of the frequency f_1 is transmitted in this manner over the junction line VL which influences relay J2 to such an extent that the short circuit for relay C2 due to the closing of contact 76j2 over: earth, contacts 76f2, 14p2 and consequently cuts off the circuit extending over the outgoing c-lead, thereby initiating the release of the succeeding connecting device also. Since the circuit for relay E2 has also been cut off on the opening of contact 45c2 this relay

is caused to release whereupon the arrangement is completely restored to normal.

If a connection is to be set up within the sub-exchange over the group selector GW1, the switch 5 is set to a level to which, for example, the repeater Ue1 is connected. When such a connection is to be set up within the sub-exchange the switch wiper sal brushes the interconnected contact segments only. Relay C1 is energized on the seizure 10 of the switch and consequently energizes relay Q over: earth contacts 10c1, 13o, relay Q, contact 14r, switch wiper 3, c-lead, contacts 15f, 16h1, resistance, battery, earth. Relay Q closes contact 28q and, at the end of the impulse series 15 which causes the switch wipers to be raised to a definite level, a circuit for relay O is closed on the release of relay V as follows: earth, battery, winding I of relay O, switch wiper sal, contacts 26v, 5a, 27r, 28q, switch wiper I, a-lead, contacts 29f, 30i 20 I, primary winding of the speaking current repeater Sp1, contacts 31j1, 32f, b-lead, switch wiper 2, contact 33r, earth. Relay Q is energized and maintained in this condition over contacts 10c1 and 34o. In addition it opens its contacts 35o and 36o causing the secondary lineswitch to be disconnected. When the c-wiper of the group selector encounters an idle repeater, relay P1 is energized in known manner. This relay closes its contact 23p1 which causes the group selector 25 to be guarded against further seizures, and also actuates contacts 24p1 and 25p1 and thereby connects the switch to the repeater.

What is claimed is:

1. In a multi-office or multi-exchange automatic telephone system, a trunk line extending from a first office or exchange to a second office, an incoming directively operable switch in the second office in which said trunk line terminates, an automatic switch in the first office, means for directly operating said automatic switch for selecting a definite traffic direction, means responsive to the setting of said automatic switch for transmitting an alternating current signal over said trunk line specific to the selected traffic direction, and means responsive thereto in the second office for setting said incoming switch to the required traffic direction.
2. In a switching system, a local switch and an outgoing switch, lines accessible to said outgoing switch, said local switch being responsive to a received series of impulses to set itself in a position depending upon the number of impulses in the series, means effective upon the termination of the series of impulses for causing said outgoing switch 55 to seize an idle one of the lines accessible thereto, and means thereupon effective and dependent upon the setting of said local switch for trans-

mitting alternating current by way of a wiper of the local switch over the line taken into use by the outgoing switch.

3. In an automatic telephone system, a trunk line, an automatic switch, means for transmitting impulses corresponding to various digits to said switch, said switch responsive to the transmission of a digit of a desired number and independent of whether said digit has any particular one of a plurality of predetermined values for operating said switch to seize said trunk line, and means also responsive to said digit and depending upon the value of the digit for transmitting a signal of alternating current over said trunk line characteristic of the value of said digit.

4. In a telephone system, a sub-exchange and a main exchange to which said sub-exchange is subsidiary, means responsive to an initiation of a call in the sub-exchange for taking a local switch for use, means responsive to the dialling of a digit indicating a number which may be reached by way of the main exchange for taking a main exchange trunk line for use and for operating said local switch to an extent dependent upon the value of the digit, and means controlled in accordance with the position assumed by said local switch for transmitting a signal over the main exchange trunk line characteristic of the value of the digit used to operate the local switch.

5. In a telephone system as claimed in claim 4, a switch in the main exchange terminating said main exchange trunk line, and means responsive to said signal for forthwith positioning said main exchange switch in accordance with the digit value indicated by said signal.

6. In an automatic telephone system, a sub-exchange and a main exchange, a directly operable switch in the sub-exchange, local lines accessible to said switch, an automatic switch associated with said first switch, trunk lines 115 accessible to said automatic switch leading to the main exchange and terminating therein in main exchange switches having access to a plurality of groups of lines, means for transmitting impulses corresponding to digits of called numbers to the 120 directive switch in the sub-exchange, said automatic switch operated responsive to the first digit to select an idle one of said trunks, said directive switch having means for transmitting a selecting impulse over the selected trunk, after seizure, of a 125 character dependent on the value of the digit transmitted to the directive switch, said main exchange switch responsive to said selecting impulse to elect a group of the lines accessible thereto.

MAXIMILIAN MATHIAS.
